BOLT-DOGGING MEANS.

1,311,304.

Specification of Letters Patent. Patented July 29, 1919.

Original application filed December 8, 1917, Serial No. 206,323. Divided and this application filed November 15, 1918. Serial No. 262,659.

To all whom it may concern:

Be it known that I, HENRY G. VOIGHT, a citizen of the United States, residing in New Britain, county of Hartford, and State of Connecticut, have invented certain new and useful Improvements in Bolt-Dogging Means, of which the following is a full, clear, and exact description.

This invention relates to means for dogging a bolt in its retracted position, the invention being illustrated in connection with a vertically sliding bolt of an emergency exit lock or so-called panic bolt of the type which is applied to the doors of school-houses, theatres, department stores, and other buildings for facilitating exit where a fire or the like causes panic, it being obvious, however, that the utility of the bolt dogging means herein disclosed is not limited to the dogging of a panic bolt.

One construction of the type of panic bolt just referred to is disclosed in my copending application, Serial No. 206,323, filed December 8, 1917, of which this case is a division.

The herein disclosed invention refers more particularly to bolt dogging mechanism wherein a door is provided with a bolt adapted to engage a keeper or strike plate on the lintel and arranged to be released from said strike plate or keeper by means of a swinging cross-bar on the inner face of the door. The bolt which engages the strike plate just mentioned is provided with dogging means for retaining the same in its retracted position and the dogging means is constructed to be automatically released as the door upon which the bolt is mounted is moved to its closed position, whereby the bolt is released to slide into engagement with its keeper or strike plate.

The primary object of the present invention is to provide improved detent means for retaining a bolt in its retracted position.

Another object of the invention is to furnish a detent device of very simple and efficient construction, which co-operates very satisfactorily with a bolt of the sliding type, which is preferably received or housed in part in a casing at the upper portion of the door, and which is automatically released.

To these and other ends the invention consists in the novel features and combinations

of parts to be hereinafter described and claimed.

55

In the accompanying drawings,—
Figure 1 is an inside elevation of part of a door equipped with a panic bolt, provided with one form of my bolt dogging means, the door being shown in its closed position.

Fig. 2 is an enlarged section on line 2—2 of Fig. 1, showing the detent device, the bolt being in the protracted position.

Fig. 3 is a view similar to Fig. 2, but 65 showing the bolt in the retracted position, and the door partly opened.

Fig. 4 is an enlarged section on line 4—4 of Fig. 1.

Fig. 5 is a view similar to Fig. 4, showing the bolt dogged in the retracted position by the sliding detent plunger.

Fig. 6 is a rear view of the casing in which the detent device is housed, with the back plate of said casing removed, the bolt being 75 in the protracted position; and

Fig. 7 is a similar view showing the bolt dogged in the retracted position.

Referring to the drawings, I have shown my improvements applied to a panic bolt 80 mechanism, embodying a bolt at the upper edge of the door for co-operating with a strike plate or keeper on the lintel and a swinging cross-bar extending across the door and adapted to retract the bolt when said cross-bar is moved. The bolt is preferably of the square head type, that is the upper end of the bolt is at right angles to its axis, instead of being beveled like a latch bolt. This type of bolt must obviously be held in its retracted position while the same is being swung into alignment with its strike plate. I, therefore, provide the sliding bolt with a detent mechanism for automatically holding the same in its retracted position, when it is released by 95 the cross-bar above mentioned, means being provided for releasing the detent automatically when the door is closed again, so that the bolt thereupon takes into its keeper.

The door A is mounted in a frame or casing B, and is adapted to open outward, as usual in doors equipped with emergency exit locks or fasteners. It will be understood, of course, that the door is hinged at the right of Fig. 1 and that the bolt mechanism is arranged adjacent the left hand edge. The

bolt mechanism includes a swinging cross-bar C, which is pivoted to the door at one end of the bar as shown at 10, and is pivoted to the casing D, adjacent the other end of the cross-bar as shown at 11. The cross-bar C is operatively connected inside the casing D to the vertically sliding bolt rods 12 and 13, the operative connection between these elements being made in any preferred manner, so that the bolt rods may be retracted when the cross-bar C is operated.

The bolt head 14 carried at the upper end of the upper bolt member 12 is partially inclosed in a rim casing 16, applied to the inner face of the door adjacent the upper edge thereof, and this rim casing 16 also partially incloses the detent mechanism which automatically dogs the bolt member 14 in its retracted position, when it has been retracted. The casing 15 has a base plate 16 with screw holes 17, by means of which it may be secured to the door. At the lower part, the casing has a guide opening for a sleeve 18 into which the upper end of the bolt member 12 is screwed. The sleeve 18 has an extension at its upper part within the casing, as indicated at 19, which is secured by screws 20 to a part 21 carried by the bolt head 14. The casing 16 is provided with a back plate 22, which is screwed to a post 23 integral with the front wall of the case. It will be understood that while in the embodiment illustrated the bolt sections 19 and 21 are separate from the section 12, these sections in conjunction constitute a rigid upper bolt member, but this is not a material feature of the invention. The detent device for holding the bolt retracted is preferably of the sliding type, being constituted by a spring pressed plunger 24 guided in the front wall in the casing 16 and having a shoulder 25 at its inner end adapted to engage a locking recess 26 in the member 21 carrying the bolt head 14. The plunger 24 is hollow, as shown in Figs. 4 and 5 and contains a spring 27. This spring is interposed between the bottom of the hollow plunger and a guide pin 28 entering the inner end of the plunger, said pin 28 being carried by the back plate 22, the arrangement being such that the plunger has a tendency to move outward in the wall of the casing, and when the locking recess 26 is in alignment with the locking flange on the inner end of the plunger, the spring will tend to seat the flange in the recess. The recess is so located relatively to the bolt head that when the flange engages said recess, the bolt is in the fully retracted position. Supposing the bolt to be in the protracted position shown in Fig. 6, the dogging plunger is prevented from moving outward by engaging a depending wing 29 on the bolt head, but when the bolt is fully retracted, the recess 26 is opposite the plunger, which then moves outward to a certain extent, under the influence of its compressed coiled spring 27, and locks the bolt in its retracted position.

It will be understood that when the bolt head 14 is retracted sufficiently to disengage the same from its keeper by the cross-bar C, the detent mechanism comes into play just as soon as the bolt is fully released and thereby locks the same in its retracted position. When the door is closed the detent is automatically released by a device associated with the keeper plate 30. This releasing device comprises a depending finger 31, cast integral with the strike or keeper 30, and extending downward therefrom so as to lie close to, but slightly in front of the front wall of the casing 16, when the door is closed, as shown in Fig. 2. As the door is closed, the outer end of the plunger 24 strikes the depending rigid releasing finger 31, and is thereby pushed inward in opposition to the spring 27. This releases the bolt, which is then immediately projected into its keeper by a protracting spring (not shown), which may be located in the casing D. When the bolt head 14 is retracted, the door opens immediately, and when it is partly opened, as shown in Fig. 3, the finger 31 is no longer in the way of the detent plunger 24, and the latter is therefore free to move into locking engagement with the sliding bolt under the influence of the spring 27. It will be seen that the detent mechanism, herein described, retains the sliding bolt in its retracted position, until the door upon which the bolt is mounted is closed sufficiently to bring the bolt substantially in alignment with its strike plate or keeper, whereupon the detent is operated to release its bolt.

Various changes may be made in the details of the construction without departing from the scope of the invention as defined in the claims, it being obvious that the detent mechanism herein disclosed may be used in connection with numerous sliding bolt constructions and is not limited in its use to panic bolts.

What I claim is:

1. In combination with a door, a rim casing applied to the face of the door near the upper edge thereof, a sliding bolt extending through the casing in a vertical direction and guided in openings at the top and bottom of the casing, a keeper on the upper part of the door frame to receive said bolt, a detent member for dogging the bolt in retracted position normally projecting outward from the front face of said casing, and a rigid depending releasing member on the keeper extending downward in front of said detent member to engage the projecting end thereof when the door is closed and thereby release the bolt.
2. In combination with a door, a casing mounted thereupon, a bolt operatively

mounted in said casing, a dogging device mounted within said casing for dogging said bolt in its retracted position, a shoulder upon said dogging device, a projection upon 5 said bolt cooperating with said shoulder for normally retaining said dogging device in its inoperative position, means for moving said dogging device into dogging position when said bolt is retracted, and means for 10 automatically releasing said dogging device when said door is closed.

3. In combination with a door and door frame, a casing applied to said door adjacent an edge thereof, a sliding bolt movable in 15 said casing, a keeper upon said door frame to receive said bolt, a hollow detent slidably mounted in said casing to dog said bolt in its retracted position, a spring housed within 20 said hollow detent and arranged to move the same into dogging position, and means upon said keeper for moving said detent out of dogging position.

4. In combination with a door and door frame, a casing applied to said door adjacent an edge thereof, a sliding bolt movable in 25 said casing, a keeper upon said door frame to receive said bolt, a detent mounted to slide transversely within said casing and movable into and out of dogging engagement with said bolt, said detent having an 30 end extending outwardly through said casing, a spring for moving said detent into dogging engagement with said bolt, and means upon said keeper positioned to engage 35 the exposed end of said detent to force

the same inward out of its bolt dogging position.

5. In a casing, a slidably mounted bolt, an inwardly directed guide pin upon a face of said casing, and means for dogging said 40 bolt against movement, comprising a hollow detent slidably mounted upon said guide pin, and a spring for moving said detent into dogging engagement with said bolt.

6. In a casing, a slidably mounted bolt, 45 an inwardly directed guide pin within said casing, and means for dogging said bolt against movement, comprising a detent slidably mounted within said casing, said detent having a socket formed in one end to slidably 50 receive said guide pin and having its opposite end protruding through a wall of said casing, and a spring for moving said detent into dogging engagement with said bolt.

7. In a casing, a slidably mounted bolt, an inwardly directed guide pin within said casing, a detent slidably mounted within 55 said casing and movable into and out of dogging engagement with said bolt, said detent having an end protruding outwardly through a wall of said casing and having a socket formed in its opposite end to slidably receive said guide pin, and a spring operatively mounted within said socket to move 60 said detent into dogging position.

In witness whereof, I have hereunto set my hand on this 12th day of Nov., 1918.

HENRY G. VOIGHT.
